ATTORNEY

UNITED STATES PATENT OFFICE.

WILLIAM VOSS, OF WILMINGTON, DELAWARE, ASSIGNOR TO AMERICAN CAR AND FOUNDRY COMPANY, OF ST. LOUIS, MISSOURI, A CORPORATION OF NEW JERSEY.

PASSENGER-CAR.

1,045,477.

Specification of Letters Patent.

Patented Nov. 26, 1912.

Application filed August 27, 1910. Serial No. 579,323.

To all whom it may concern:

Be it known that I, WILLIAM VOSS, residing at Wilmington, Delaware, and being a citizen of the United States, have invented 5 certain new and useful Improvements in Passenger-Cars, of which the following is a full, clear, and exact description, such as will enable others skilled in the art to which it appertains to make and to use the same, 10 reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is a view in side elevation of a portion of a car embodying the features of the invention, parts being broken away for increasing the disclosure. Fig. 1^a is a view supplemental to Fig. 1, which, with Fig. 1, discloses approximately one-half of a car. Fig. 2 is a transverse, vertical section taken approximately on the plane indicated by line 2—2 of Fig. 1, and looking in the direction of the arrow, substantially one-half of the car being broken away. Fig. 3 is an enlarged, detail, 25 fragmentary, vertical section taken on the plane indicated by line 3—3 of Fig. 1^a. Fig. 4 is a similar view taken on the plane indicated by line 4—4 of Fig. 1^a, but further enlarged. Fig. 5 is an enlarged, horizontal, detail, fragmentary section taken on the plane indicated by line 5—5 of Fig. 3, looking downwardly. Fig. 6 is a similar view taken on the plane indicated by line 6—6 of Fig. 4, looking downwardly. Fig. 7 is 30 a detail, perspective view of a fragment of two window sills and a fragment of the sheathing intervening between windows, the parts being seen detached. Fig. 8 is an enlarged, detail, fragmentary, longitudinal, horizontal section, taken approximately on the plane indicated by line 8—8 of Fig. 1. Fig. 9 is an enlarged, detail, fragmentary elevation of one of the upper corners of one of the door frames viewed from within the 45 car. Figs. 10 and 11 are sections taken respectively on the plane indicated by line 10—10, and the plane indicated by line 11—11 of Fig. 9. Fig. 12 is an enlarged, detail, fragmentary vertical section taken

on the plane indicated by line 12—12 of 55 Fig. 2.

Referring to the drawings by numerals, 1, 1 indicate the side connecting members of the underframe, shown in detail in my companion application on improvements in 60 underframes for cars filed even date here-with, each of said side connecting members comprising an angle having a vertical, up-standing leg or flange and an inwardly directed horizontal flange.

Rising vertically from each member 1 are pairs of side posts 2, 2, each post comprising a Z-section having its lower end crimped inwardly for accommodating the vertical flange of the respective member 1, the outer 70 flange of each post 2 being riveted to the vertical flange of the respective member 1. The crimp of the lower end of each post 2 provides an offset which allows the portion of the outer flange of each post 2 above 75 member 1 to extend with its outer face substantially flush with the outer face of the vertical flange of the respective member 1. A pair of posts 2 is arranged between each two of the several window openings, and 80 near the ends of the car a post 2' similar to one of the posts 2 is arranged at the edge of the window opening. Each of the posts 2 and 2' extends upwardly to the side plate 3, which plate is preferably of angle section 85 having its vertical leg depending and its horizontal leg extending inwardly. The outer flange of each post 2 and 2' is riveted to the inner surface of the depending leg or flange of plate 3.

At various points spaced along the length of the car opposite sets of posts 2 are connected by main carlines, each comprising a pair of angles 4, 4 with an interposed channel 5. Each angle 4 comprises a continuous 95 bar extending from side plate to side plate and being bent to form lower and upper deck sections, the ends of the several angles 4 being connected, as best shown in Fig. 3 by splice plates 6 to T-rails 7, said T rails 100 extending along and within the respective side of the car and being fixed to the upper ends of the posts 2. Each channel 5 is made up of sections, a section 5^a constituting the lower deck portion of the carline and having 105 its lower end fixed by a bracket plate 8 to the horizontal flange or leg of the respective side plate 3. Each section 5^a is bent at the inner

edge of the lower deck to an upstanding portion 5^b which extends upwardly to and is connected by a bracket plate 9 to the web of the upper deck section 5^c at a point spaced inwardly from the respective end of section 5^c, thus leaving overhanging end portions of each section 5^c. Each of the main carlines comprised of members 4 and 5 is incased by plates 4^a, 4^b and plate 4^c. Each lower deck is also sustained by short carline sections 17^a spaced along the car at intervals intermediate the main carlines.

Roof plate 10 covers sections 5^c and overhangs the ends thereof, being formed with down-turned flanges 10^a. At each side of the upper deck and extending longitudinally thereof, is the screen plate 11 having its lower edge portion secured by bolts 12 to the lower edge portion of ventilator window plate 13, which also extends longitudinally at each side of the upper deck. The upper edge portions of each of plates 11 and 13 extend between the ends of carline sections 5^c and the respective flange 10^a, a plate 14 being disposed between plate 11 and the given flange 10^a. The plate 14 preferably assumes the form of a longitudinal strip bent outwardly intermediate its edges and outstanding below the flange 10^a to form a water table 15. Brackets 16 are preferably provided for connecting the flange 10^a plate 14 and plates 11 and 13 to the sections 5^c, said brackets being riveted to the respective parts. Plate 13 is preferably formed with a horizontal portion near its upper edge so that the main body of the plate is set inwardly from plate 11 and the lower edge portion of plate 13 is bent in conformity to the shape of the lower deck, lapping and being fixed to the lower deck roof plate 17. Window frames 18 are disposed in suitable openings in plate 13 at intervals along the length of the car and riveted to said plate, each frame 18 retaining a window sash 19.

The lower deck roof plate 17 depends below the lower ends of carlines 5 outside the respective side plate 3, and the facia plate or letter board 20 has its upper portion extending along and in contact with the depending flange of the respective plate 3, the facia plate 20 extending downwardly to the window openings and being connected adjacent its lower edge to window frame bars 33^a, fillers 21 being interposed between the lower edge portion of plate 20 and the bars, said bars being fixed to the outer flanges of posts 2. A longitudinal strip or plate 22 is interposed between plate 20 and the roof plate 17, and said plates 20 and 22 are connected to plate 3 and plate 17 by through rivets. The plate 22 preferably assumes the form of a longitudinal strip having its lower portion bent outwardly for forming a water table 23.

A sheathing plate 24 is fixed to the upper standing flange of member 1, and is of a

width causing it to extend upwardly to the window openings, and of a sufficient length to extend from end to end of the car, said plate being fixed to the outer flanges of the posts 2 and 2'. A window sill plate 25 preferably extends from end to end of the car, said plate lapping the upper edge portion of the plate 24 and, at the point of each of the window openings, being formed with extensions bent inwardly across the edge of the plate 24 for the width of the side posts, said extensions being inclined and being shaped to form the window sills proper.

A belt rail 26 extends from end to end of each side of the car and rests flat against the depending portion of the respective window sill plate 25, said belt rail being fixed to the posts 2 and 2' by through rivets engaging the outer flanges of said posts. Between each two adjacent window openings, each plate 25 is formed with an upstanding longitudinal flange 27 and transverse flanges 28, 28 rising from the inclined portion of the plate, said flanges being snugly inclosed in each instance by the lower end of a channel-shaped pier cover plate 29; there being one plate 29 between each two adjacent window openings, the web of the plate extending across the space between the posts 2 of a given set and being riveted to the outer flanges of said posts, and the turned flanges of the respective plate 29 extending past the edges of the outer flanges of the posts 2 and carrying preferably resilient weather strips 30, 30 adapted in operation to engage the outer surface of the lower sash 31 of the respective windows. Each of the window openings is filled by a lower sash 31 which is vertically slideable and retained by inner stops 32, and an upper rigidly mounted sash 33 which extends longitudinally from the web of one post 2 to the web of the post at the opposite side of the window opening, the flange of each plate 29 being cut away at its upper inner portion for accommodating the rigidly mounted sash 33. Each stop 32 is provided with the usual curtain guide 32^a, and the inner edges of the posts 2 of each set are inclosed by a channel-shaped plate 34, having its flanges extending outwardly between the inner portions of the respective stops 32 and filler blocks 35, which blocks are interposed between the stops and the webs of posts 2.

Extending longitudinally of the car at each side and fixed to the inner flanges of the posts 2 is an angle 36 upon which rests the supplemental floor plate 37, a similar angle 38 being fixed at each side to the posts 2 above angle 36 for sustaining the main corrugated floor plate 40, which latter plate sustains the concrete floor 41. An insulating medium 42 is preferably disposed as a filler between plates 37 and 40. An inner lining plate 43 is fixed to the inner flanges 130

- of posts 2 below the window openings and extends longitudinally throughout the length of the car, the upper edge portion of each plate 43 being connected by angle sections 44 to the inner edge portions of the inwardly extending sections, or window sills proper, of the respective plate 25. A sill boxing or plate 45 incloses the inner edge of the sill proper and is formed with the usual outwardly facing vertical shoulder for receiving the lower edge of sash 31, the inner edge portion of plate 45 being turned downwardly, lapping and being fixed to the upper edge portion of plate 43.
- 15 Each side connecting member 1 is connected at each end by a bracket plate 46 with the respective end sill 47 of the under-frame, and a corner plate 48 rises from the bracket and extends upwardly to the lower edge of the lower deck, the lower end of plate 48 being formed with a depending intermediate portion left by the cutting away of edge portions, the said depending intermediate portion lapping a portion of bracket 46 and being riveted thereto. A plate 49 is arranged at each corner engaging post 2' at one edge and having its other edge engaging plate 48; the edge engaging the post 2' is similar in formation and arrangement to the corresponding edge of any one of the plates 29 previously described. A corner coverplate 50 incloses the plate 48 and the outer edge of the respective plate 49 and also incloses the outer edge of the end 35 sheathing 51 and the end of the side sheathing 24. A carline 52 is arranged at each end of the car and extends from side plate to side plate and is formed similarly to each carline member 4, each carline 52 being spaced inwardly from the end of the car. A carline 53 is arranged adjacent each end of the car and corresponds in general outline to the carline members 5 but is formed with the lower deck sections 5^a extending directly across the car from one of the plates 3 to the other. The upstanding portion 5^b is, in this instance, a separate member and is secured to the upper face of the member 5^a by suitable brackets as 5^d.
- 40 The opposite ends of the carline 53 engage the plates 3 immediately above the corner plates 48, and the plates 3 extend beyond the corner plates 48 and are riveted to the ends of the hood plate 54. The facia plate 55 20 is also extended to and about and fixed to the hood plate 54. Upper and lower deck hood carlines 55 and 56 extend from carline 53 to hood plate 54, and of course are covered by a roof plate not illustrated.
- 45 In the car structure herein illustrated the end of the car is formed with a doorway, the end wall being provided between the doorway and each side with end posts 57, 58 and 59, each comprising a channel extending from the end sill 47 up to the lower deck sections of the end carline. The end sill 47 comprises a channel having its web disposed vertically and its flanges extending inwardly and severed or cutaway for accommodating the posts 57, 58 and 59, a bottom cover plate 61 being arranged beneath and fixed to the lower flange of the end sill 47, upon which bottom cover plate the ends of the posts 57, 58 and 59 rest. Plate 61 preferably has its outer end fixed to the horizontal flange of member 1 and its inner end bent into a depending portion fixed to the web of an I-beam center sill 62, of which there are preferably two. An end gusset plate 63 rests upon and is fixed to the upper flange of end sill 47, the end posts 57, 58 and 59 extending through said gusset plate 63 and being fixed thereto and to the upper flange of end sill 47 by brackets 64, 64.
- 50 Between the posts 57 is arranged the door casing seen in Fig. 2, and in detail in Figs. 9, 10 and 11, and comprising uprights or posts 65 connected by lintel 66 to which and to the posts 65 is fixed the jamb 67, said uprights and lintel being preferably covered by a particular plate 68. Each of the posts 65 and the lintel 66 is preferably formed of an angle plate having its angle opening outwardly and toward the doorway, and each of the flanges or legs of the angle having its outer portion bent or formed with a right angularly disposed flange 65^a. One of the legs of each member 65 snugly receives the jamb 67, which is preferably of wood, and is bolted to the adjacent flange of the member 65. The horizontal portion of the jamb is similarly connected to the lintel 66. The outer flange 65^b of each member 65 and of lintel 66 is riveted to the end wall of the car and to the outer edge portion of the corner cover plate 68. The outstanding leg of each post or member 65 is fixed to plate 63 and to the upper flanges of the respective I-beam platform extension sill 69 by an angle bracket 70. The upper end of each of said posts 65 is fixed by an angle bracket 71 to the outstanding leg of lintel 66 and to an angle bracket 72 by through rivets, the bracket 72 being in turn fixed to the web of the adjacent post 57. Each post or member 65 has its inner flange 65^a fixed by an angle bracket 73 to the corresponding flange of the lintel 66.
- 55 20 What I claim is:—
1. In a car, the combination with a side connecting member, of Z-section side posts arranged in pairs and fixed to and extending up from said side connecting member, a side plate connecting said posts, the several pairs of posts being spaced for forming window openings, an exterior channel plate inclosing the outer portion of each pair of side posts, and an interior

channel plate inclosing the inner edges of each pair of posts.

2. In a car, the combination of side posts, each comprising a Z-section, an exterior channel plate engaging and inclosing the flange of each of two of the side posts, and an interior channel plate for each two of the posts inclosing the inner edges and flanges thereof.

3. In a car, the combination of side posts, 10 each comprising a Z-section arranged with its web disposed transversely of the car, the inner flange of each post being directed toward the other post and the outer flanges outstanding longitudinally of the car, and 15 an interior plate inclosing the inner flanges of the post.

4. In a car, side posts, each comprising a Z-section, an exterior channel plate inclosing the outer portions of the posts, an interior channel plate inclosing the inner portions of the posts, fillers between the flanges of one of said channel plates and the posts, and sash stops engaging said fillers and the 25 respective contiguous channel plate.

5. In a car, side posts, each comprising a Z-section, an exterior channel plate inclosing the outer portions of the posts, an interior channel plate inclosing the inner portions of the posts, fillers between the flanges of one of said channel plates and the posts, and sash stops engaging said fillers and the 30 respective contiguous channel plate, the flanges of the other channel plate being 35 formed with sash stops.

6. In a car, the combination with pairs of side posts spaced for providing window openings between each two pairs, a bar con-

necting the post of one pair with the adjacent post of the next pair across the upper end of the window opening, a sill plate 40 extending longitudinally of the car across the planes of a plurality of window openings and having window sill portions extending from the plate across the space below the window opening, a channel plate inclosing the outer portions of the posts of each pair, a fixed sash extending across the upper portion of the window opening from post to post and let into the flanges of the 50 respective channel plates, each of said flanges being provided with an exterior window stop, an interior window stop spaced therefrom, and a movable sash slidingly disposed between said stops out of 55 the planes of the fixed sash.

7. In a car, the combination of side posts, each comprising a Z-section, an interior channel plate for two of the posts inclosing the inner edges thereof, filler blocks intermediate the inner edges thereof and the interior channel plate.

8. In a car, the combination of side posts, each comprising a Z-section, an interior channel plate for two of the posts inclosing 65 the inturned flanges of the Z-section, filler blocks between the channel flanges and Z-shaped section webs and within the out-turned flanges of the Z-section side posts.

In witness whereof I have hereunto set 70 my hand in the presence of two witnesses.

WILLIAM VOSS.
